UNITED STATES PATENT OFFICE.

HERMAN ABRAMS, OF PHILADELPHIA, PENNSYLVANIA, ASSIGNOR TO CRESCENT
BRASS MFG. CO., OF READING, PENNSYLVANIA.

DESIGN FOR A COLUMN FOR LIGHTING FIXTURES.

Application filed June 11, 1924. Serial No. 9,846. Term of patent 7 years.

To all whom it may concern:

Be it known that I, HERMAN ABRAMS, a citizen of the United States, and a resident of Philadelphia, county of Philadelphia, and State of Pennsylvania, have invented a certain new, original, and ornamental Design for a Column for Lighting Fixtures, as shown in the accompanying drawings, in which—

Fig. 1 is an elevational view of a column for lighting fixtures showing my new design; and

Fig. 2 is a plan view of the same.

I claim:—

The ornamental design for a column for lighting fixtures substantially as shown.

In witness whereof, I have hereunto set my hand this 24th day of May, 1924.

HERMAN ABRAMS.
